UNITED STATES PATENT OFFICE.

HENRY L. FERRIS, OF HARVARD, ILLINOIS, ASSIGNOR TO HUNT-HELM-FERRIS & COMPANY, OF HARVARD, ILLINOIS, A CORPORATION OF ILLINOIS.

PIG-GUARD.

1,283,712.

Specification of Letters Patent.

Patented Nov. 5, 1918.

Application filed August 11, 1917. Serial No. 185,699.

To all whom it may concern:

Be it known that I, HENRY L. FERRIS, a citizen of the United States, residing at Harvard, in the county of McHenry and 5 State of Illinois, have invented a new and useful Improvement in Pig-Guards, of which the following is a specification.

My invention relates to certain new and useful improvements in pig guards and is 10 fully described and explained in the specification and shown in the accompanying drawings, in which:

Figure 1 is an elevation of a part of a pig-pen showing the guard; Fig. 2 is a section on the line 2 of Fig. 1; Fig. 3 is a similar view with the guard extended, and Fig. 4 is a section on the line 4 of Fig. 2.

Referring to the drawings, 5 are posts supporting a bottom bar 6 which in turn 20 supports vertical bars or uprights 7. Pivoted on two of these uprights are guard arms 8 each having a vertical bar 9 surrounding the uprights. One arm also has two flanged perforated projections 10 and 25 11 at right angles to each other. The arms pivotally support by their ends a guard bar 12.

When the guard is out of use it is swung back against the wall of the pig-pen and the 30 perforation in the projection 10 then registers with the corresponding perforation in the bottom bar 6, so that the guard may be locked in its retracted position by a pin 13. When the guard is to be used, it is swung 35 out from the wall of the pig-pen and is locked by passing the pin through the perforation in the projection 11. (See Fig. 3.)

The present structure is exceedingly simple, strong, efficient and readily assembled. 40 I realize that considerable variation is possible in the details of this construction without departing from the spirit of my invention; therefore I do not intend to limit myself to the specific form herein shown and 45 described except as pointed out in the fol-

lowing claims, in which it is my intention to claim all the novelty inherent in the construction as broadly as is permitted by the state of the art.

What I claim as new and desire to secure 50 by Letters Patent is:

1. In combination with the wall of a pig-pen, a guard comprising two arms swinging in a horizontal plane on vertical pivots on the wall, a bar supported by the free ends of the 55 arms to be swung therewith to and from the wall, said arms when in their extended position supporting said bar at a height above the floor of the pen sufficient to permit the smaller pigs to pass thereunder but to exclude the larger pigs, and means to lock the arms in extended position or against the wall.

2. In combination with the wall of a pig-pen, a guard comprising two arms swinging 65 in a horizontal plane on vertical pivots on the wall, an arm having radial perforated projections to register with a corresponding stationary perforation, a bar supported by the free ends of the arms, and means engaging 70 said perforations to lock the arms in extended position or against the wall.

3. In combination, a pen wall comprising horizontal and vertical members, two arms pivotally supported upon the vertical members 75 of the wall and swinging around the same as axes, and a guard rail pivotally supported by the free ends of the arms and adapted to be swung therewith toward or from the wall, said arms when in their extended position supporting said guard rail at a height above the floor of the pen sufficient 80 to permit the smaller pigs to pass thereunder but to exclude the larger pigs, and means for locking the arms to hold the 85 guard rail in extended or retracted position.

In testimony whereof, I have hereunto set my hand this 26th day of July, 1917.

HENRY L. FERRIS.
